UNITED STATES PATENT OFFICE.

HUGH KARNEY McMANUS, OF VICKSBURG, MISSISSIPPI

WASHER AND STERILIZER.

Application filed June 17, 1926. Serial No. 116,651.

This invention relates to an improved machine for sterilizing and washing ice cream scoops, glasses, and similar utensils used in association with soda fountains.

5 Briefly the invention comprises a tank, in which a utensil rack is mounted for rotation, this rack being constructed to hold the scoops against displacement, and being rotated by a hydraulic motor.

10 My principal aim is to provide a simple and inexpensive structure of this class which is practical, sturdy, efficient in operation, and capable of accomplishing the desired results in an efficient manner.

15 Other features and advantages of the invention will become apparent from the following description and drawings.

In the accompanying drawings, forming a part of this application, and in which 20 like numerals are employed to designate like parts throughout the same:

Figure 1 is a view in section and elevation of the complete machine.

Figure 2 is a top plan view with the 25 cover of the tank in open position.

Figure 3 is a perspective view of the scoop rack.

Figure 4 is a perspective view of a portion 30 of the piping, valve controls, and hydraulic motor.

Referring now to the drawings by reference numerals, it will be observed that the reference character 1 designates a casing or tank which is preferably of the configuration shown in Fig. 2. This tank may be constructed of sheet metal, the same being preferably open at its top and the open top being closed by a hinged lid or cover 2. Located inside of the tank, on the opposite side walls are shelves 3 for supporting glasses and similar articles.

A revolving rack is supported in the tank for rotation. This rack, as better shown in Fig. 3 comprises a substantially circular base plate 5, a rotating shaft 6, and a cage for holding the various utensils. The cage comprises a multiplicity of vertically disposed circumferentially spaced rods connected with the base plate, and held together by a central ring 8.

Also connected with the uprights, and associated with the ring 8 are upper and lower annular members which are provided with a multiplicity of small rings 9 and 10 respectively.

The base plate 5 is formed with water

circulating holes 11 and it carries, on its top, a plurality of circumferentially spaced circulating vanes 12. These vanes are of angular formation, and are obliquely disposed with respect to the axis of rotation and are located over the water circulating holes 11. The purpose of the vanes is to set up a strong agitation of the water to aid in cleaning the utensils supported on the rack.

The vanes act somewhat as baffle plates also, and any water which is collected therebeneath, escapes downwardly through the water holes 11. The shaft 6 on the bottom 70 of the base plate is mounted for rotation in the bottom of the casing or tank in any appropriate manner. In addition, the casing is, in turn, supported on a frame 13 carried by uprights 14.

75 Novel means is disposed beneath the frame and casing for supplying water to the tank and for operating the revolving rack. The means embodies a plurality of pipe fittings, and couplings arranged in an orderly and compact manner, as shown better in Fig. 4. Reference being had to this figure, it will be seen that this means comprises principally a housing 15 for a fluid-motor 15^a, (see Fig. 1).

80 In this connection, it might be stated that the shaft 6 on the bottom of the rack extends down and is connected with this rotor. Thus, these parts operate to provide a hydraulic motor.

85 Connected to one side of the housing 15 is a water intake which is connected through the medium of couplings and pipe fittings with control valves 17 and 18, located in hot and cold water supply pipes, leading 90 from any suitable source of supply. Leading from the opposite side of the housing is a discharge neck 19, which is coupled to a T-shaped coupling 20.

95 Connected with the coupling 20 we find 100 branch pipes 21 and 22 which are in turn connected with independent control valves 23 and 24. Incidentally, operating rods or stems are provided for operating these valves 23 and 24 and are substantially provided on their control ends with hand grips 105 25 and 26. The valve 24 is connected with a water discharge pipe 27 on the upper end of which is an elbow 28.

110 This elbow constitutes a drain and is connected at the bottom of the tank on one side. Connected to the bottom on an opposite side

is a similar elbow 29, which leads from the valve 23. A plug 31 having a handle 32 is located in the rear compartment of the tank as shown in Fig. 1, and serves to control the flow of water from the tank back down through the elbow 28 and into the discharge pipe 27.

In operation, water under pressure is supplied to each one of the pipes 17 or 18, through the intake 16 of the hydraulic motor. The motor is thus operated, which in turn serves to rotate the rack 4 thru the medium of the shaft 6. When the machine is first started, the valve 24 is closed, while the valve 23 is opened. This allows the water to flow through the coupling 20, the branch 21, valve 23, and elbow 29, into the tank until the tank is substantially full of water.

The rotation of the rack within this water and the agitation of the water itself caused by the rotation serves to cleanse the article supported on the track. When sufficient water is in the tank, for cleaning purposes, the valve 23 is closed. However, at this time, the valve 24 is now open, allowing the water which is running the hydraulic motor, to flow down through the discharge pipe 27. When however, the water in the tank becomes heavily laden with grease, and dirt, and it is desired to drain the tank, then the plug 31 is lifted, allowing the water to drain down through the elbow 28 and into the pipe 27. Of course the valve 23 is again opened to refill the tank.

If desired, a brush 30 may be suitably mounted on the central portion of the rack to aid in cleaning the utensils. The brush of course, affects no cleaning while the rack is in rotation, but enables the operator to scrub off some of the particles of dirt from the utensils before they are placed upon the rack for agitation in the water.

The construction and operation of the device will undoubtedly be clear by considering the description in connection with the drawings. Therefore, a more lengthy description is deemed unnecessary.

While the preferred embodiment of the invention has been shown and described, it is to be understood that minor changes coming within the field of invention claimed may be resorted to as desired.

I claim:

1. In a structure of the class described, a tank adapted to be filled with water, a utensil supporting and carrying rack located in said tank, a shaft carried by said rack and journaled for rotation in a bearing in the bottom of the tank, a hydraulic motor disposed beneath the shaft and including a housing and a rotor adapted for rotation in said housing, said shaft being connected with said rotor, a fluid intake connected with one side of the motor housing, fluid supply means connected with said intake, a discharge neck on the opposite side of the housing, a T-coupling connected with said discharge neck, branch pipes connected with said T-coupling and extending in opposite directions, a valved elbow connected with one branch pipe and also connected with said tank for supplying water to said tank, a valved discharge pipe connected with the remaining branch pipe, a drain elbow connected with said tank and with said discharge pipe, and a control plug for said discharge pipe.

2. In a washer and sterilizer of the class described, a tank, and a utensil supporting rack located in said tank, said rack comprising a base plate, an operating shaft connected with and depending from said base plate, a plurality of circumferentially spaced vertically disposed uprights connected to and rising from said base plate, vertically disposed annular members connected with said uprights, said annular members being provided with relatively small rings, said base plate being provided with water circulating holes, and a plurality of circumferentially spaced radially extending vanes mounted on the top of the base plate over the holes, said vanes being of right angular form.

In testimony whereof I affix my signature,

HUGH KARNEY McMANUS.
